UNITED STATES PATENT OFFICE.

MELVIN SOLOMON GROH, OF TORONTO, ONTARIO, CANADA, ASSIGNOR TO JOSEPH MERCADANTE, OF NEW YORK, N. Y.

REFRIGERATOR-COOLING MEANS.

Application filed February 4, 1924. Serial No. 690,622.

To all whom it may concern:

Be it known that I, MELVIN SOLOMON GROH, a subject of the King of Great Britain, and a resident of the city of Toronto, in 5 the county of York, in the Province of Ontario, Canada, have invented certain new and useful Improvements in Refrigerator-Cooling Means, of which the following is the specification.

10 My invention relates to improvements in refrigerator cooling means and the object of the invention is to devise a cooling element comprising a liquid refrigerant container into which all the liquid refrigerant will 15 enter from a fluid controlled valve together with any surplus lubricating oil that may be carried into the system from the pump in such a way that any of the oil that may congeal at the valve due to its becoming cold 20 will on the stopping of the circulation of the refrigerant warm up and flow away from such valve.

A further object is to devise means for securing circulation of the refrigerant liquid 25 to the float chamber of the valve by the reduction of pressure of the gas that flows into the float chamber along with the liquid refrigerant due to a reduction in temperature of such gas by the metal contact of the 30 float chamber with the cold pipe of the cooling element.

A still further object is to devise means for obtaining the cooling effect in the cooling element without the necessity of the refrigerant liquid being fed under pressure throughout the entire length of such cooling 35 element.

Another object is to devise means whereby the admission of the liquid refrigerant to the 40 liquid refrigerant container is effected while such liquid is traveling upward and yet another object is to devise removable ice making means embodied in the cooling means which will utilize a portion of the cooling 45 element capacity and which when removed will enable the proportion of the cooling element capacity so used to be used for increasing the cooling effect.

My invention consists of refrigerator cooling means constructed and arranged all as 50 hereinafter more particularly described and illustrated in the accompanying drawing in which:

Fig. 1 represents a vertical section through

a refrigerator provided with my cooling 55 means, taken on the line 1-1 Figure 2.

Fig. 2 is a horizontal section on the line 2-2 Figure 1.

Fig. 3 is a vertical section through the liquid refrigerant container and one of the 60 loop tubes of the cooling element showing the means attached to the latter for increasing the cooling effect without increasing the amount of refrigerant liquid used.

Fig. 4 is a perspective view of the refrigerant liquid container showing a modified form of cooling means applied thereto.

Fig. 5 is a perspective detail showing the liquid container and cooling tubes applied to an ice-cream container.

Fig. 6 is a vertical section of the float controlled valve showing it applied to the liquid refrigerant container.

Fig. 7 is a perspective detail of the rack for supporting the removable ice containers, 75 and

Fig. 8 is a perspective detail of one of such containers.

Like characters of reference indicate corresponding parts in the different views.

1 is the liquid refrigerant container provided with the longitudinal horizontal baffle-plate 2. 3 are depending loop tubes communicating at their upper end with the refrigerant container 1, said tubes being preferably spaced apart and positioned in the vicinity of one side of the interior of the refrigerator 4. 5 are hollow fins on each loop tube 3 preferably being secured thereto by being brazed or soldered so as to homogeneously connect the fins to the tubes. 6 is the casing of the valve and 7 is the fluid chamber thereof provided with a cock 8 in its top.

9 is the cold pipe formed integrally with 95 the valve casing and connected at its upper end to the liquid refrigerant container 1. The lower end of the cold pipe 9 is provided with the valve 10 adapted to seat on the seat 11. The stem 12 of the valve 10 is pivotally connected to one end of the intermediately fulcrumed lever 13, its other end being pivotally connected to the float 14 which is capable of vertical movement in the float chamber 7, depending on the level of liquid therein.

15 is a passage-way connecting the cold pipe 9 with the float chamber 7. 16 is a liquid refrigerant pipe by means of which

the liquid refrigerant in the system is adapted to flow into the float chamber 7. 17 is an outlet pipe from the liquid refrigerant container 1.

5 In the modified cooling element illustrated in Figure 4 it will be noted that the loop tubes 3 are disposed in a plane running through the longitudinal axis of the liquid refrigerant container 1 and a single hollow 10 fin is used connected to the respective loop tubes.

In the form illustrated in Figure 5 in which the cooling elements are shown in multiple for use with ice-cream containers, 15 instead of fins 5 circular hollow containers 18 are provided, the loop tubes being then of spiral form and homogeneously connected to such containers 18. In this case the liquid refrigerant containers 1 are mounted on the 20 sides of the containers 18.

The hollow fins 5 or the containers 18 are adapted to contain a freezing liquid such as water or brine so that when the machine is operating, the suction pressure of the system 25 will not drop below that necessary to freeze the water or brine until it is practically all frozen, thus extracting latent heat from the water or brine and permitting the system to function to a more efficient suction pressure. 30 The frozen brine thaws and absorbs heat long after the machine has stopped.

The pipes 16 and 17 are respectively connected to the condensing chamber 22 and pump of the refrigerant apparatus. The latter is not shown or described as it forms no part of the present invention. I prefer to use, however, the apparatus disclosed in my co-pending applications for refrigerating machines Serial Number 533,905, filed February 3, 1922, and pumps, Serial Number 40 533,906 filed February 3, 1922.

With the liquid refrigerant that flows from the condensing chamber to the float chamber 7 there is a certain proportion of refrigerant gas which on entering the float chamber is reduced in pressure due to its decrease in temperature owing to the metallic contact of the cold pipe 9 with the float chamber casing with the result that 45 some of the gas is condensed which tends to make the pressure in the float chamber 7 lower than that in the condensing chamber 22 and thus induces a flow of gas and liquid refrigerant from such condensing 50 chamber 22 to the float chamber 7.

The float chamber 7 also serves to accumulate any air or foreign gas that may happen to be in the system. This entrapped air or gas may then be purged out of the 60 system by opening the pet cock 8 without losing much of the refrigerant gas.

Upon the level of the liquid in the float chamber 7 rising it raises the float 14 and consequently opens the connected valve 10, 65 permitting the liquid refrigerant to flow up-

wardly through the cold pipe 9 into the liquid refrigerant container 1 and when the height of liquid falls the float falls correspondingly, closing such valve.

As the cooling effect is produced in the 70 cooling elements which consist of the liquid refrigerant container 1, depending loop tubes 3 and the attached fins 5, the liquid refrigerant in the tubes effervesces, the bubbles of gas rising into the liquid refrigerant 75 container 1 wherein such gas is dispelled from such liquid refrigerant container 1 through the pipe 17 into the pump, due to its suction. The baffle plate 2 in the liquid refrigerant container 1 is so constructed as 80 to permit the gas to pass around it and flow into the upper side of such container, from whence it is expelled as above stated. This baffle plate is preferably constructed of a material that will be attacked by any 85 acid that may be in the refrigerant, neutralizing the same, and, if desired, an additional acid neutralizing material may be inserted into the container, such as the corrugated plate 19. The most prevalent acid 90 found in the preferable refrigerant, which is sulphurdioxide, is sulphurous acid and in this case the baffle 2 and the plate 19 will be constructed of iron.

Such baffle plate also serves to stop the 95 liquid refrigerant from splashing up and being carried out of the pipe 17 with the outgoing gas.

The racks 20 are adapted to be inserted between the tubes 3 if desired, and upon 100 these racks are placed the containers 21 which are adapted to contain water which is frozen when the system is in operation and thus provide means for making ice for domestic purposes. Obviously it would be 105 possible to freeze any other goods if placed on these racks instead of the water containers 21. When these water containers are not in use it will be apparent that the cooling effect produced by the cooling elements 110 will be increased and can be used for cooling the refrigerator.

From the above description it will be seen that I have devised a simple and effective 115 cooling means for refrigerating machines in which the congealing of any surplus lubricating oil that may get into the system from the pump will be prevented from choking the valve 10 by its congealing about the same, due to the fact that such liquid 120 refrigerant is fed into the cooling element in an upwardly traveling direction and thus the oil will float up through the cold pipe 9 into the liquid refrigerant 1, lying on the top of the liquid refrigerant therein and being 125 carried off in small globules with the outgoing gas that is drawn through the pipe 17. In addition I have devised means for making ice for domestic purposes, in the cooling element, that will only decrease the 130

cooling effect of such cooling elements when the ice is being made in direct proportion to the amount being made.

- Moreover I have devised cooling means 5 that will effect an increased cooling effect for the quantity of refrigerant used and in which the refrigerant will not be compelled to traverse the entire length of all the coils but will be fed independently into each loop 10 tube directly from the liquid refrigerant container due to the fact that the refrigerant in the tube effervesces and becomes gas which rises through the remaining liquids in the tubes into such refrigerant container. 15 It will be readily seen that my cooling element permits an entirely free circulation of the air in the refrigerator as well as exposing large areas of cold surface to the circulating air.
- 20 What I claim as my invention is:

1. In refrigerating cooling means, a cooling element comprising a container adapted to hold liquid refrigerant, individual tubes

substantially U-shaped, their open ends connected to the container, and members homogeneously connected to said tubes, said members being hollow and adapted to be filled with liquid. 25

2. In refrigerating cooling means, a container, adapted to contain liquid refrigerant 30 with acid forming properties, and a baffle disposed horizontally in the container and filling substantially the entire length of said container, said baffle having both of its sides out of contact with the inner surface of the 35 container, said baffle being constructed of material adapted to neutralize the acid formed from said liquid refrigerant.

3. In refrigerating cooling means, a container adapted to contain a liquid refrigerant with acid forming properties, and a baffle in the container, said baffle being constructed of material adapted to neutralize 40 the acid formed from said liquid refrigerant.

MELVIN SOLOMON GROH.
